INVENTOR

RICHARD C. HOSKINSON

BY Arthur L. Sles.
ATTY.

UNITED STATES PATENT OFFICE.

RICHARD C. HOSKINSON, OF SAN FRANCISCO, CALIFORNIA.

FLUE BASE.

Application filed March 15, 1926. Serial No. 94,783.

My invention relates to improvements in flue bases wherein a metal receptacle is embedded within a non-inflammable block installed in connection with the floor and wall 60

5 structure of a building to receive the lower end of a flue and provided with a cleaning outlet communicating with the bottom thereof whereby the base may be cleaned.

The primary object of my invention is 10 to provide an improved flue base adapted to form an efficient and fire proof mounting for the lower ends of flues and the like.

Another object is to provide an improved 15 flue base provided with a receptacle forming a soot catcher and having an outlet adapted to facilitate the cleaning of the base and flue.

A further object is to provide an improved 20 device of the character described which may be easily installed and which may be readily adapted to different forms of flue and wall construction.

A still further object is to provide an improved device which, as an article of manufacture, can be economically produced.

I accomplished these and other objects by 25 means of the device disclosed in the drawings, forming a part of the present application wherein like characters of reference 30 are used to designate similar parts throughout said specification and drawings and in which,

Fig. 1 is a vertical section of my improved flue base.

35 Fig. 2 is a horizontal section taken upon the line 2—2 of Fig. 1 in the direction indicated.

Fig. 3 is a vertical section showing a slightly modified form of the cover plate.

40 Referring to the drawings the numeral 1 is used to designate a block of non-inflammable material such as cement or other material molded into a desired shape and form. Within the block 1 is embedded a metallic 45 receptacle consisting of a body portion 2 preferably of cylindrical form closed across the bottom by a bottom portion 3 and having its upper end extending slightly above the top of the block 1.

50 An outlet portion 4 is formed integrally with the body portion 2 of the receptacle, said outlet portion being preferably rectangular in cross section and extending outwardly through one side of the block 1 to rest upon a floor plate or other portion of a building, not shown. The bottom of the outlet

portion 4 is preferably formed as a continuation of the bottom portion of the body 2 to form a continuous flat surface across the bottom of the base member.

60 A cover member 6 is arranged to normally close the outwardly extending end of the outlet portion 4, said cover being preferably arranged to be slidably engaged within the portion 4 and made of a sufficient length to 65 permit said cover to form an extension of the portion 4 whereby the distance to which said portion 4 extends outwardly may be adjusted to different widths of floor plates or wall structures as required. The cover 70 member 6 is movable outwardly to give access to the interior of the receptacle through the portion 4. The outer end of the cover member 6 may be made of any desired or- 75 nate character where the same is placed in an exposed position about the building.

A metal plate 7 is applied upon the top of the block 1, said plate having a central opening arranged to fit over the outwardly extending end of the body portion 2 of the 80 receptacle. The plate is embedded in the top of the block 1 and forms a permanent footing for a flue 8 fitted onto the outwardly extending portion of the body 2 of the receptacle. In the case of flues made of terra 85 cotta or other similar material, the plate 7 is recessed around the outwardly extending end of the portion 2 to receive the lower end of the flue, the bottom end of the flue being engaged between the outwardly extending 90 end of the body 2 and an annular shoulder 9 spaced sufficiently therefrom to receive the flue, as shown in Fig. 1 of the drawings. A second annular shoulder 11 is spaced from the shoulder 9 and arranged to engage the 95 lower end of a jacket 12 of the character commonly provided around flues of this nature. For metal flues and flues not requiring a jacket, the plate 7 may be made flat upon its upper surface as shown in Fig. 100 3, the lower end of such flue being sufficiently held by the outwardly extending end of the portion 2 without the provision of an outer retaining shoulder.

In operation, my improved base is in- 105 stalled in connection with the adjacent floor and wall portions of a building with the outlet portion 4 extending outwardly through the adjacent wall portion to give convenient access to the interior of the base 110 for cleaning, the cover member 6 being adjusted to conform to the particular build-

ing structure. The device thus constitutes a stable and fireproof base forming an efficient footing for the flue and affording ready access to the interior of the base for cleaning.

When it is desired to clean the base, the cover member 6 is removed outwardly and any soot or débris accumulated in the base may be removed by means of a suitable 10 scraper, the continuous flat bottom 3 of the receptacle permitting the base to be easily cleaned.

The metal receptacle is preferably cast as a single element. The receptacle may be embedded in the cement block 1 by placing the member in a suitable form into which the cement is subsequently poured, thus forming a complete article of manufacture ready for installation, or the receptacle may be set in 20 position within a building and the cement poured around the member after it has been so set. In either case, the cement block forms a stable and fireproof setting whereby said base may be permanently held in position.

The specific form and construction of the device is of course subject to modification in the specific details of construction and arrangement. I therefore do not wish to restrict myself to the precise details of constructions illustrated and described, but wish to avail myself of all modifications which may fall within the scope of the appended 30 claims.

Having thus described my invention, what I claim as new and desire to secure by Letters Patent is,

1. A flue base comprising a cement block; a receptacle embedded within the block; and 40 a cleaning outlet portion connected into the receptacle and extending outwardly through a side of the block to permit the cleaning of the base.

2. A flue base comprising a cement block; a receptacle embedded within the block; and a cleaning outlet portion connected into the receptacle and extending outwardly through a side of the block to permit the cleaning of the base; and means for normally closing the outlet portion.

3. A flue base comprising a cement block; a receptacle embedded within the block; a cleaning outlet portion connected into the receptacle and extending outwardly through 55 a side of the block to permit the cleaning of the base; and a cover member slidably connected to the outlet portion for normally closing the same, said cover member being adjustable to conform to different widths of 60 wall structure.

4. A flue base comprising a cement block; a receptacle embedded within the block; and a cleaning outlet portion formed integrally with the receptacle and extending outwardly 65 through a side of the block to permit the

cleaning of the base, said outlet portion extending outwardly past the side of the block and being arranged to be received within an adjacent wall structure.

5. A flue base comprising a cement block; 70 a receptacle embedded within the block; a cleaning outlet portion formed integrally with the receptacle and extending outwardly through a side of the block to permit the cleaning of the base, said outlet portion extending outwardly past the side of the block and being arranged to be received within an adjacent wall structure; and a cover member 75 slidably connected to the outlet portion and arranged to extend through said wall structure, said cover member being arranged to be withdrawn to give access to the receptacle through the outlet portion.

6. A flue base comprising a cement block; 80 a receptacle embedded within the block and extending outwardly through the top thereof; an outlet portion formed integrally with the receptacle and extending outwardly through a side of said block; and a plate 85 having an opening arranged to fit over the outwardly extending end of the receptacle, said plate being embedded in the top of the block.

7. A flue base comprising a non-inflammable block; a receptacle embedded within the block and having one end extending outwardly slightly past the top of said block; an outlet portion formed integrally with the receptacle and extending outwardly through a side of the block; and a plate embedded in the top of the block and having an annular recess formed around said outwardly extending end of the receptacle to receive the lower end of a flue.

8. A flue base comprising a non-inflammable block; a receptacle embedded within the block and having one end extending outwardly slightly past the top of said block; an outlet portion formed integrally with the receptacle and extending outwardly through a side of the block; and a plate embedded in the top of the block and having an annular recess formed around said outwardly extending end of the receptacle, said plate being provided with spaced annular shoulders formed within the recess to receive the lower ends of a flue and a casing surrounding 110 said flue.

9. A flue base comprising a non-inflammable block; a receptacle embedded within the block and having one end extending outwardly slightly past the top of said block; an outlet portion formed integrally with the receptacle and extending outwardly through a side of the block; and a plate embedded in the top of the block and having an annular recess formed around said outwardly extending end of the receptacle, said plate be- 115 120 125 130

ing provided with spaced annular shoulders formed within the recess to receive the lower ends of a flue and a casing surrounding the flue; and a cover member connected to the outlet portion for normally closing the same and removable therefrom to give access to the body portion for cleaning.

10. As an article of manufacture, a flue base comprising a cement block; a metallic receptacle embedded within the block, said

of the block; an outlet portion formed integrally with the receptacle and extending outwardly through a side of the block; a plate fitted around the outwardly extending end of the receptacle and embedded in the top of the block; and a cover member detachably connected to the outlet portion for normally closing the same.

In witness whereof I hereunto set my signature.

RICHARD C. HOSKINSON.
